UNITED STATES PATENT OFFICE.

HERBERT W. WOLFF, OF ST. LOUIS, MISSOURI, ASSIGNOR TO AMERICAN CAR & FOUNDRY COMPANY, OF ST. LOUIS, MISSOURI, A CORPORATION OF NEW JERSEY.

END BRACING FOR CARS.

No. 823,838.

Specification of Letters Patent. Patented June 19, 1906.

Original application filed December 11, 1905, Serial No. 291,257. Divided and this application filed March 19, 1906, Serial No. 306,815.

To all whom it may concern:

Be it known that I, HERBERT W. WOLFF, a citizen of the United States, residing at the city of St. Louis, State of Missouri, have invented a certain new and useful Improvement in End Bracings for Cars, of which the following is a full, clear, and exact description, such as will enable others skilled in the art to which it appertains to make and use the same, reference being had to the accompanying drawings, forming part of this specification, in which—

Figure 1 is an elevation of the end of a gondola car provided with my improved end-wall brace. Fig. 2 is an enlarged vertical sectional view on the line 2 2 of Fig. 1, and Fig. 3 is a perspective view of my improved brace.

This invention relates to the construction of cars, and particularly to that type known as "gondola" cars, and has for its object to provide a novel form of brace for stiffening the end wall of the car intermediate its upper and lower edges and tying the same to the side walls of the car.

Referring to the drawings, which represent the preferred form of my invention, 1 and 2 designate, respectively, the end and side walls of a car provided at their upper edges 30 with angles 3. The novel end-wall brace, which forms the subject of this invention, preferably consists of a web portion 4, which is widest at the center of the car and thence tapers toward the sides of the car, said web being provided at its inner edge with an upwardly-extending flange 6, which lies against the end wall of the car intermediate its upper and lower edges and is connected thereto by rivets 7 and provided at its outer edge with a 40 downwardly-projecting flange 7^a, which preferably is shallowest at its middle portion and thence gradually increases in depth toward the sides of the car. At the ends of the brace these flanges are bent around the side 45 walls of the car and are connected thereto by rivets.

My improved brace not only strengthens the end wall of the car intermediate its upper and lower edges and prevents the same from 50 buckling, but is also of sufficient strength to

carry vertical loads, and thus provides a shallow platform or step which affords a footing at the end of the car.

Having thus described the invention, what is claimed as new, and desired to be secured by Letters Patent, is—

1. A brace for strengthening the end wall of a car intermediate its upper and lower edges consisting of a plate bent to present a horizontal portion with legs or flanges at its 60 opposite edges extending in opposite directions; substantially as described.

2. A brace for strengthening the end wall of a car intermediate its upper and lower edges consisting of a plate bent to present a 65 horizontal portion widest at the center and legs or flanges at each edge which extend in opposite directions; substantially as described.

3. A brace for strengthening the end wall 70 of a car intermediate its upper and lower edges consisting of a plate bent to present a horizontal portion widest at the center, and oppositely-extending legs or flanges which are bent around the corners of the car and secured to the side walls thereof, the portions of said flanges which are bent around the corners of the car being separated from each other by means of slits formed in said plate; 75 substantially as described. 80

4. An end brace for cars having a horizontal portion and an upwardly-extending flange at its inner edge which is secured to the end wall of the car intermediate its upper and lower edges, and a downwardly-extending leg or flange at the outer edge of said horizontal portion; substantially as described. 85

5. An end brace for cars consisting of a horizontal portion having an upwardly-extending leg or flange at its inner edge which 90 is secured to the end wall of the car intermediate its upper and lower edges, said horizontal portion being widest at its center and provided with a downwardly-extending leg or flange at its outer edge; substantially as 95 described.

6. An end brace for cars consisting of a horizontal portion widest at its center and provided with an upwardly-extending leg or flange at its inner edge which is secured to 100

the end wall of the car intermediate its upper and lower edges, and a downwardly-extending leg at its outer edge, both of said flanges extending around the corners of the car and being secured to the side walls thereof; substantially as described.

In testimony whereof I hereunto affix my

signature, in the presence of two witnesses,
this 14th day of March, 1906.

HERBERT W. WOLFF.
